SHOE BOX

Marvin W. Vannice, Burbank, Calif., assignor to Vue-Chest, Inc., Burbank, Calif., a corporation of California

Filed Jan. 19, 1959, Ser. No. 54,228

Term of patent 14 years

(Cl. D58—12)

Fig. 1 is a perspective view showing the front, top and one side of a shoe box embodying my new design;

Fig. 2 is an elevational view of the side shown in Fig. 1, the opposite side being substantially the same;

Fig. 3 is a bottom plan view of the shoe box; and

Fig. 4 is a rear view of the shoe box, taken from the right side of Fig. 2.

The design for the shoe box disclosed is characterized by the two side members having the configurations as shown.

I claim:

The ornamental design for a shoe box, substantially as shown and described.
